UNITED STATES PATENT OFFICE.

JOSEPH FINBERG AND CHARLES T. HELLER, JR., OF ST. PAUL, MINNESOTA.

NON-REFILLABLE BOTTLE.

1,362,564.

Specification of Letters Patent. Patented Dec. 14, 1920.

Application filed May 10, 1919. Serial No. 296,066.

To all whom it may concern:

Be it known that we, JOSEPH FINBERG and CHARLES T. HELLER, Jr., citizens of the United States, residing at St. Paul, in the 5 county of Ramsey and State of Minnesota, have invented a new and useful Improvement in Non-Refillable Bottles, of which the following is a specification.

Our invention relates to a non-refillable 10 bottle, and particularly to a non-refillable stopper construction to prevent the refilling of a bottle after the same is filled and our stopper is attached thereto. The non-refillable stopper is of a simple, inexpensive 15 construction, having a suitable valve means for closing the bottle against being refilled in any position.

The invention further provides means for 20 protecting the valve and discharge openings of the non-refillable stopper, to prevent tampering with the valve for the purpose of refilling the bottle. Means are provided to assist the action of the valve to always 25 close the bottle discharging opening when the bottle is in an upright position.

The invention further provides a catching 30 channel or recess about the lower edge of the protecting hood, which is formed with a pouring lip to allow liquid to be easily 35 poured from the bottle and to prevent the same from running down around the non-refillable stopper, thereby providing a clean, non-refillable stopper for the bottle, which will not become unsightly from the 40 contents of the bottle running down the sides of the same from the stopper. Means are also provided in our non-refillable stopper to hold the stopper valve closed to secure the bottle for shipment and before it 45 is desired to use the contents thereof. In this manner, no extra cork is required to close the bottle when it is being shipped and before any of the contents of the same have been poured out, a suitable seal being 50 provided to hold the valve in closed position.

In the drawing forming part of this specification:

Figure 1 is a side view of our non-refillable 55 stopper attached to the neck of a bottle, only a portion of the bottle being illustrated.

Fig. 2 is a plan view of the non-refillable stopper.

Fig. 3 is a vertical cross section on the 55 line 3-3 of Fig. 2.

Fig. 4 is a view of the non-refillable stopper in a pouring position and partly illustrated in cross section.

The non-refillable stopper A is formed 60 with a body portion 1, which is rigidly secured to the neck B of any suitable bottle by means of the annular collar 2, the upper and lower edges of which are crimped in at 65 3 and 4 to engage an annular groove 5 formed in the lower portion of the body 1 of the stopper A, and the shoulder 6 of the neck B, respectively. A washer 7, of rubber or other resilient material, is inserted between the neck B of the bottle and the base 70 portion of the stopper A, the same being compressed sufficiently to form a liquid tight joint between the neck B and the stopper A, while the collar 2 is crimped to the stopper and neck. In this manner, the 75 stopper A is held rigidly and with a liquid tight joint to the neck B of the bottle. The sealing washer 7 is formed with a central opening 8, which connects with the opening 9 in the neck B of the bottle, and is normally closed when the bottle is in upright position by the valve 10, which is freely positioned in the vertically extending chamber 11, formed in the body portion 1 of the 80 non-refillable stopper.

The valve 10 is formed of sufficiently 85 heavy material to cause it to normally close the opening 8 by gravity, when the bottle is in an upright position, but the valve is free to move upward in the chamber 11 when the bottle is tipped into an angular or upside down position, sliding the valve into the upper portion of the chamber 11, as illustrated in Fig. 4, opening the passageway 8 and allowing the liquid in the 90 bottle to be discharged out of the passageway 9 and through the opening 8 into the lower portion of the chamber 11. Suitable 95 openings 12 are formed in the sides of the chamber 11, through which the liquid passes 100 when the valve is in upright position, as illustrated in Fig. 4, to discharge the liquid from the bottle.

The valve 10 is freely movable in the 105 chamber 11 and is frusto-conical in shape, being slightly smaller in diameter at the top than at the bottom, to prevent it from sticking in the chamber 11, and insuring its free movement therein. The valve is formed with a depending seat 13, which extends into the opening 8 and assists in centering and balancing the valve when it comes into 110

closed position. The opening 8 in the sealing washer 7 is slightly smaller than the diameter of the chamber 11, thus causing the lower outer edge of the valve 10 to engage against the sealing washer 7 to form a closing valve for the non-refillable stopper A.

A helical spring 14 is rigidly connected in any suitable manner to the upper surface of the valve 10 at 15 at the small end of the helical spring 14, and the large end of the spring 14 engages around the inwardly projecting nipple 16 in the upper portion of the chamber 11. The spring 14 is of a delicate nature, having only a slight expanding force so as to assist the valve 10 to return to closing position when the bottle is turned or righted, after it has been turned upside down to discharge the contents from the bottle, the spring 14 being only for the purpose of overcoming the friction of the valve 10 against the sides of the chamber 11. In this manner, the valve closes quickly as the bottle is righted and brought back to an upright position after having discharged some of the liquid from the same.

By the aid of the spring 14, the valve 10 is prevented from engaging against the sides of the chamber 11, to hold the valve in a partially opened position, even when the bottle and stopper are turned slowly to a horizontal position, thus causing the valve to close quickly and preventing the refilling of the bottle when the same is held in a horizontal position. The valve 10 is of sufficient weight to overcome the pressure of the spring 14 when the bottle is held in an angular discharging position, as illustrated in Fig. 4.

A hood 17 is provided to protect the openings 12 and is formed with a depending flange 18, which extends annularly about and is spaced from the lower portion of the outer surface of the body portion 1, to form an outlet passageway for the openings 12, to allow the liquid contained in the bottle to pass out of the openings 12 and under the depending flange 18. The hood 17 engages against the projecting annular shoulder 19, formed on the outer portion of the body 1 of the stopper, and a spring lock ring 20, of ordinary construction, is adapted to engage in annular recesses formed in the hood and the body portion 1 to lock the hood 17 in position on the body portion of the stopper. In constructing the stopper A in this manner with the hood 17 separate from the body portion of the same, the stopper gives a simple construction to manufacture, but it is obvious, however, that the hood can be formed integral with the body portion, if it is so desired, and when it is held in place by the lock ring 20, it performs the same functions as if it were integral with the body portion 1 of the stopper. The flange 18 acts as a petticoat to protect the openings 12 and

to prevent anything being inserted into the openings so as to allow tampering with the valve 10.

An upwardly extending and outwardly flaring annular flange 21 is formed integral with the lower portion of the body of the stopper 1, and which extends about the lower depending petticoat flange 18, forming an annular collecting recess 22 about the lower edge of the flange 18. The recess 22 will collect and hold the small amount of liquid which is not discharged out of the flange and stopper when the bottle is righted or brought to an upright position, after having poured some of the liquid out of the same, in this manner preventing any liquid which may have collected in the stopper while pouring from the bottle running down the side of the bottle and giving an unsightly appearance. This liquid remaining in the collecting recess 22 may also form a seal about the lower edge of the depending flange 18 and thus sealing the inner portions, such as the valve 10 of the non-refilling stopper, from the outer atmosphere, if it is so desired. The space between the flange 22 and the lower edge of the petticoat flange 18 is very small and being only sufficient to allow the desired amount of liquid to be discharged from the non-refillable bottle. The flange 21 is higher on one side than the other and extends outwardly to form a pouring lip 23, and the depending petticoat flange 18 is also extended toward the lip 23 at 24. In this manner, the petticoat flange 18 will assist in directing the liquid from the bottle, when pouring out of the same, toward the pouring lip 23 and therefore form a convenient means for discharging the liquid from the bottle and preventing the liquid from being flushed out and over the entire non-refillable stopper. It is equally important that a convenient pouring means be arranged in a non-refillable bottle, or the liquid being discharged from the bottle will be flushed over the entire stopper, giving an undesirable result.

Means are provided in our non-refillable stopper for holding the valve 10 in a closed position and to provide a seal which must be broken before the bottle can be opened. It is desirable in the use of bottles to provide a seal, and with our construction, the seal which is provided is practical for use in shipping the bottle and also in sealing the same so that no one can tamper with the contents of the bottle without breaking the seal. The seal consists in passing a suitable cord 25 through opposite openings 12 and over the top of the valve 10 before the hood 17 is in place on the body of the stopper. Notches 26 are formed in the upper edge of the flange 21 to hold the cord 25 in place over the same, and the cord 25 is extended down to the neck B of the bottle where it

is sealed beneath a suitable seal 27, which extends annularly about the neck B and which may bear any inscription that is desired. Before the cord 25 can be removed, 5 the seal 27 must be broken and thus the contents of the bottle can not be tampered with, without injuring and removing the seal.

This construction of non-refillable stopper for bottles gives a simple, inexpensive device, in which the valve 10 performs the 10 functions of a cork and seal for the stopper. The weight of the valve 10 is sufficient to hold it against the washer 7 to seal the contents of the bottle and prevent refilling 15 through the stopper A.

It is obvious that our non-refillable stopper can be so formed as to be attached to any design of bottle neck, the form illustrated being only suggestive of a simple, 20 well-known construction of bottle and we desire to protect our invention for any suitable use within the scope of the following claims:

1. The combination with a bottle, a non-refillable stopper having a valve chamber therein, a frusto-conical valve freely slideable in said chamber, discharge openings connecting said chamber with the outer atmosphere, a depending petticoat flange extending about and in close proximity to said 25 openings to cover said openings and protect said valve, an upwardly extending outwardly flaring annular flange formed on the base of said stopper to form a pouring and collecting flange and sealing means detachably connected to said valve to hold the same in a closed position for the purposes specified.

2. The combination with a bottle, a non-refillable stopper comprising a valve cham-

ber, a weighted valve freely slideable in said chamber, openings connecting said valve chamber with the outer atmosphere, a sealing cord adapted to engage said valve to hold it in closed position, means depending 45 over and in close proximity to said discharge openings for engaging said sealing cord to cause it to press downward on said valve and means for sealing the ends of said cord to the neck of said bottle to form a seal for 50 said valve to hold it in closed position for the purposes specified.

3. The combination with a bottle, a non-refillable stopper, a weighted valve freely slideable in said stopper, a hood for protecting 55 said valve, means for locking said hood to said stopper against disengagement therefrom, resilient means secured to said valve adapted to overcome the friction of said valve in said stopper to cause the same to be 60 forced into closed position when said stopper is held horizontally and a pouring flange extending about and flaring away from said hood, said flange and hood forming a seal when liquid from said bottle and stopper is 65 collected in said flange and said stopper is in an upright position for the purposes specified.

4. The combination with a bottle, of a non-refillable stopper having a smooth upper 70 closed end, discharge openings formed in the sides of said stopper, means for protecting said openings, a weighted valve freely movable within said stopper and a pouring lip forming a catching recess below said discharge openings and said protecting means 75 for the purposes specified.
